UNITED STATES PATENT OFFICE.

DAVID K. BRYSON, OF PITTSBURG, PENNSYLVANIA.

WAVE-POWER MOTOR.

SPECIFICATION forming part of Letters Patent No. 639,352, dated December 19, 1899.

Application filed February 20, 1899. Serial No. 706,158. (No model.)

To all whom it may concern:

Be it known that I, DAVID K. BRYSON, a citizen of the United States of America, residing at Pittsburg, in the county of Allegheny and 5 State of Pennsylvania, have invented certain new and useful Improvements in Wave-Power Motors, of which the following is a specification, reference being had therein to the accompanying drawings.

10 My invention relates to certain new and useful improvements in wave-power motors.

This invention relates to that class of apparatus commonly known as "wave-power motors," in which the motion of the device is 15 transmitted through the hereinafter form of connected mechanism for the production and transmission of power for mechanical and other purposes.

The object of the invention is to provide a 20 simple, efficient, and easily-constructed wave-power motor in which the motion of the waves from any direction, whether regular or irregular, horizontal or vertical, will be utilized and which will consequently prevent 25 the loss of motion inseparable from all apparatus of this class with which I am acquainted.

The apparatus which I have devised to accomplish this object consists, essentially, of a series of buoyant floats or buoys and weights 30 operating within a suitable open structure built in and above the water, and these floats or buoys and weights are connected to a suitable mechanism mounted upon the said structure. The buoys or floats and weights are so 35 suspended as to be permitted to move freely either vertically or horizontally and to be tossed about irregularly by the waves, which will have free access to them, and all of these motions are transmitted to the mechanism 40 mounted above and connected to the floats or buoys and weights, and thus converted into power for general and special purposes.

My invention finally consists in the novel 45 combination and arrangement of parts hereinafter more fully described, and particularly pointed out in the claims.

In describing the invention in detail reference is had to the accompanying drawings, forming a part of this specification, wherein 50 similar figures of reference indicate corresponding parts throughout both views thereof, and in which—

Figure 1 is a side view of my improved wave-power motor. Fig. 2 is a diagrammatical view showing the endless cable or belt, 55 the weights and buoys being removed.

Referring to the drawings by reference-numerals, 1 indicates an open structure or pier built out, in, and above the water and composed of an upright 1' and horizontal timbers 60 2 2' of suitable strength to sustain the power-transmitting devices carried by it. This pier is a skeleton structure open at all sides to give free access to the waves and may be of any shape desired. The horizontal timbers 65 2 2' have connected thereto the shafts 3 3', on which are mounted the pulley-wheels 4 4'. The pulley-wheels 4 4' are operated by an endless chain, cable, or belt 5, which operates over the same. One of the pulley-wheels 4 70 is formed integral with the power-wheel 5, upon which is mounted the power-transmitting belt 7, this belt being connected to a point where it is desired to have the power center. To allow of the proper operation of 75 the endless chain, cable, or belt, I mount on one end of the horizontal timbers 2 2' the pulley-wheels 8 8', which are arranged at right angles to the series of pulley-wheels 4 4'.

9 indicates a buoy having a pair of uprights 80 10 arranged on the upper face thereof, to which are pivotally connected the gripping-arms 11. This buoy may be of any desired shape or construction.

12 indicates a weight having a pair of uprights 13 connected to its upper face, to which are pivotally connected the gripping-arms 14, which are formed integral with the weights 14'; but if desired these arms may be provided with springs (not shown) instead of the 90 weights. These weights are of a specific gravity to insure their floating, just enough buoyancy so that they will rise with the waves. The gripping-arms 11 are so arranged that they will grip the endless chain, cable, or belt 95 on the upward movement of the buoy, and the gripping-arms 14 so arranged that they will grip the endless chain, cable, or belt on the downward movement of the weight.

It is thought that the operation of my improved motor can be readily understood; but I will state that the movement of the waves will elevate the buoys or weights, causing the buoy to immediately grip the chain, cable, or

belt and transmitting motion thereto until the force of the wave is spent. As the waves recede, the gripping-arms of the weights will grip the cable on the downward movement of the weight, which will transmit motion to the chain, cable, or belt, causing the same to move in a like direction as given it by the buoy. This upward and downward movement of the weights and buoys will keep the endless chain, cable, or belt in a continual motion, which will operate the power-wheel, thereby operating the belt 7 and transmitting power to the desired point. It will be observed that the structure or apparatus is illustrated in Fig. 1 is a portion of a series of these frames which are arranged in any desirable manner and that as many weights and buoys may be employed as desired.

Having thus fully described my invention, what I claim as new, and desire to secure by Letters Patent, is—

1. A wave-power motor consisting of an open structure or pier, a series of pulley-wheels arranged in the upper portion thereof, a series of pulley-wheels arranged in the lower portion thereof, an endless chain, cable or belt operating over the said pulley-wheels, and a series of weights and buoys operated by the waves for operating the said cable, substantially as set forth.
2. A wave-power motor consisting of an open structure or pier, a series of pulley-wheels suitably connected thereto, an endless chain, cable or belt operating over the said pulley-wheels, a series of buoys and weights carrying means for gripping the said cable for operating the same when operated by the waves, substantially as set forth.
3. In a wave-power motor an open structure or pier, a series of pulley-wheels suitably connected thereto, an endless cable, chain or rope operating over the said pulley-wheels for obtaining power, a series of floats operated by the waves adapted to grip the said chain, cable, or rope on the upward move-

ment of the said floats, and a series of weights operated by the waves adapted to grip the said chain, cable or rope on the downward movement of the weights, substantially as set forth.

4. In a wave-power motor an open structure or pier, a series of pulley-wheels suitably connected thereto, an endless chain, cable or belt operating over the said pulley-wheels, a series of buoys, and grips suitably connected to the said buoys adapted to engage the said chain, cable or belt on their upward movement thereby operating the same, substantially as set forth.

5. In a wave-power motor an open structure or pier, a series of pulley-wheels suitably connected thereto, an endless chain, cable or belt operating over the said pulley-wheels, a series of weights, and grips suitably connected to the said weights adapted to engage the said cable on their downward movement thereby operating the same, substantially as set forth.

6. In a wave-power motor an open structure or pier, a series of pulley-wheels suitably connected thereto, an endless chain, cable or rope operating over the said pulley-wheels, a series of buoys, grips suitably connected to the said buoys adapted to engage the said chain, cable or rope on their upward movement thereby operating the same, a series of weights, grips suitably connected to the said weights adapted to engage the said chain, cable or rope on their downward movement thereby operating the same, and means connected to one of the said pulley-wheels for transmitting the power created by the operation of the endless chain, cable or rope to the point desired, substantially as set forth.

In testimony whereof I affix my signature in the presence of two witnesses.

DAVID K. BRYSON.
